DAVID DECKER, OF NEW YORK, N. Y.

Letters Patent No. 105,049, dated July 5, 1870.

IMPROVEMENT IN FORMER FOR BENDING AND GLUING THE CASES OF GRAND PIANOS.

The Schedule referred to in these Letters Patent and making part of the same.

To all whom it may concern:

Be it known that I, DAVID DECKER, of the city, county, and State of New York, have invented a new and useful Improvement in Formers for the Gluing of the Rims of the Cases of Grand Pianos and other articles having a reversed double curvature; and I do hereby declare that the following is a full, clear, and exact description, reference being had to the accompanying drawing forming part of this specification, in which—

Figure 1 is a plan view, showing a former, constructed according to my invention, for gluing the case of a grand piano.

Figure 2 is a plan view, on a smaller scale, of the formers heretofore commonly employed for the same purpose.

The curved side and rear end of the rim of the case of a grand piano-forte is commonly made by gluing together five or six thin and flexible strips of wood. The several strips are bent, and the gluing effected upon a former, to which the whole is clamped and secured until dry. The former which has heretofore been employed has been made in one piece, as shown in fig. 2, its exterior side or face, *a a'*, having a form exactly corresponding with that of the interior of the rim to be produced, and the rim has been formed entirely upon this side or face.

The object of my invention is to obviate the necessity and difficulty of bending and gluing upon a hollow face; and to provide for forming all the curved portions of the rim upon rounded former surfaces; and to this end,

It consists in a former of the peculiar double or divided construction shown in fig. 1, which I will now proceed to describe.

A and *B* are two distinct pieces, which together constitute the former, and

C represents the back and side portions of the rim of a grand piano case formed thereon.

The piece *A* of the former has its face or exterior surface partly rounded, as shown at *a*, to a suitable form for the back portion of the rim *C* to be formed

around it, and partly straight, as shown at *b*, to conform to the straight portion *f* of the said rim.

The piece *B* has its face partly rounded, as shown at *c*, to conform to the hollow outer surface of the portion *d* of the rim *c*, and partly straight, as shown at *e*, to conform to the straight portion *f* of the said rim.

The straight portion, *b*, of the piece *A*, and the straight portion *e* of the piece *B*, are each made of a length nearly equal to that of the straight portion *f* of the said rim, so that when the former is in use the two straight portions *b* and *e* may overlap each other, and serve to hold the straight portion *f* of the rim between them, when the two are clamped together by screw-clamps.

To form the portion *c* of the rim of the piano-case with this former, it having been heated, and the strips of wood of which the rim is to be formed; and the veneers to cover them having been heated and coated with glue, the said strips and veneers are placed together between the straight portions *b* and *e* of the two pieces *A* and *B* of the former, with sufficient portions of their length protruding from between the said portions of the former to form the curved portions of the rim. The two portions *b* and *e* are then tightly clamped together upon the interposed portions of the strips and veneers, and the portions of the strips and veneers beyond are then bent around and clamped by screw-clamps upon the two rounded surfaces *a* and *c* of the two pieces, upon which the whole is then left to dry.

What I claim as my invention, and desire to secure by Letters Patent, is—

The former, consisting of two pieces, *A* and *B*, having the curved portions of their faces *a c*, and with straight lapping portions, *b e*, substantially as herein shown and described, for the purpose set forth.

D. DECKER.
